Primary Examiner—Stella M Reid*Assistant Examiner*—Shanda C Hill(74) Attorney, Agent, or Firm—Michael Best & Friedrich LLP(57) CLAIM

I claim the ornamental design for a profile and corner cap for a refrigerated display case, as shown and described.

DESCRIPTION

FIG. 1 is a perspective view of a profile and corner cap for a refrigerated display case embodying the present invention;

FIG. 2 is a front view thereof;

FIG. 3 is a side view thereof; and,

FIG. 4 is a top view thereof.

The broken lines shown in the drawing disclosure are for illustrative purposes only and form no part of the claimed design. The broken line(s) which define the bounds of the claimed design form no part thereof.
